United States Patent Office

Des. 180,647
Patented July 16, 1957

180,647

FLASHLIGHT

Herman G. Graubner, New York, N. Y.

Application September 17, 1956, Serial No. 42,971

Term of patent 14 years

(Cl. D48—24)

Fig. 1.

Fig. 2.

Fig. 3.

Fig. 4.

Fig. 1 is a front perspective view of a flashlight showing my new design, and showing in broken lines an optional lanyard attached to the flashlight;

Fig. 2 is a side elevation thereof;

Fig. 3 is a front elevational view; and

Fig. 4 is a rear elevational view.

I claim:

The ornamental design for a flashlight, substantially as shown and described.
